UNITED STATES PATENT OFFICE

93,391

DESIGN FOR A TEAPOT OR SIMILAR ARTICLE

Harold Graham, Pomona, Calif., assignor to Patco, Inc., Los Angeles, Calif., a corporation of California

Application April 30, 1934, Serial No. 51,591

Term of patent 7 years

To all whom it may concern:

Be it known that I, HAROLD GRAHAM, a citizen of the United States, residing at Pomona, in the county of Los Angeles and State of California, have invented a new, original, and ornamental Design for a Teapot or Similar Article, of which the following is a specification, reference being had to the accompanying drawing, forming part thereof.

Fig. 1 is a perspective view of the teapot or similar article.

Fig. 2 is a side view of the teapot or similar article.

Fig. 3 is a rear end view of the teapot or similar article.

Fig. 4 is a sectional view taken substantially as indicated on the line 4—4 of Fig. 2.

The design shown in the accompanying drawing is characterized by the dominant feature of downwardly diverging flutings at each corner of the container of the teapot or similar article.

I claim:

The ornamental design for a teapot or similar article substantially as shown and described.

HAROLD GRAHAM.
